E. E. Overholt,
ATTORNEY.

UNITED STATES PATENT OFFICE

JESSE F. MADDEN, OF BROOKLYN, NEW YORK

TRAVERSE BUTTON

Application filed May 1, 1930. Serial No. 449,000.

My invention relates to traverse buttons such, for instance, as are used on quilling machines, which button is usually though not necessarily made of porcelain and is usually carried by a metal finger or arm.

This button is, in some respects, an improvement on my button which forms the subject matter of my application for patent Ser. No. 320,932, dated Nov. 21, 1928.

10 In using traverse buttons made of both porcelain and metal, the buttons are usually held to the work by metal holders which are provided in their outer ends with jaws having a cutaway space between them of a size 15 and shape adapted to snugly receive the shanks of the buttons.

It is unavoidable that these jaws very frequently become sprung a trifle, and in such cases it is common to cement or shellac the 20 buttons into their holders to make them hold securely in order to prevent the loosening and falling out caused by vibration. This cementing or shellacking process consumes no little time; and one of the objects of the present invention is to provide means for removably locking the buttons on their respective 25 holders without the use of shellac or cement. This feature of the present invention is not embraced in the previous application just 30 above referred to.

A very important feature of the present invention consists in the construction of its working face, which is not predominantly spherical, as is ordinarily the case with buttons of this character; but on the contrary is predominantly cylindrical in the direction of the travel of the button when at work. The object of this feature is to insure the production of a cone very evenly and tightly wound. 35 This gives a decided advantage in coppering silk, since the silk is sold on the cops, and is sold by the pound, and a certain sized cop 40 is figured to have a given weight. If half-pound cops or pound cops are desired, the 45 machine is set accordingly. The figuring

must then be made as to how tightly and how evenly the coppering should be done in order to insure that the given sized cone for which the machine is set shall yield the desired weight. If it fails to do so, as is often 50 the case with the ordinary traverse button, the cops are bound to weigh less, besides being unevenly coppered; and hence an unsalable article is produced.

Another important feature of the invention 55 consists in providing the button with a shank sufficiently long to project up above the holder enough to carry locking means in said projecting portion for securing the button in the holder.

The object of the present invention is therefore twofold, namely; to secure the traverse buttons on their respective holders without the use of shellac, cement, or the like; and to insure the production of tightly and evenly wound cops of uniform weight.

The invention consists in certain novel features of construction and arrangement of parts, as will now be specifically described and claimed, reference being had to the accompanying drawing, in which;

Fig. 1 is a top plan view of the usual metallic holder used for holding traverse buttons on quilling machines.

Fig. 2 is a view of the same with my improved traverse button secured thereon in operative position.

Fig. 3 is a similar view showing slightly modified means for securing the button on the metallic holder.

Fig. 4 is a side view of the device, as illustrated in Fig. 3, and, Fig. 5 is a side view of Fig. 2.

Fig. 6 is a top plan view of the form of button shown in Fig. 2; and, Fig. 7 is a similar view of the form of button shown in Fig. 3.

Fig. 8 is a view of the wire spring holder used with the form of button shown in Figs. 2, 5, 6, and 9.

Fig. 9 is a side view of Fig. 6.

Fig. 10 is a side view of Fig. 7, with the securing pin omitted. Fig. 11, is a perspective of said securing pin.

5 Fig. 12 is a bottom plan view showing the working face of my improved button; and,

Fig. 13 is a sectional view taken on the line 13—13 of Fig. 7, with the securing pin omitted.

10 The numeral 1 designates the metal holder, such as in common use in quilling machines, said holder being provided at its outer end with a bent-up section 2 for engagement with the frame of the machine; and at its forward 15 end with opposing jaws 3 for engaging and holding the traverse button. The numeral 4 designates the traverse button which has a shank 4a adapted to be snugly received into the semi-circular space 5 between the 20 jaws 3 of the holder. This shank 4a is provided on its opposing circular sides with parallel grooves 6 into which is received a spring wire 7 for locking the button in its holder, as shown in Figs. 2 and 5. The portion 25 4b at the base of the shank, between the button proper and the grooves 6, is of a depth equal to the thickness of the metal holder 1.

30 In the modified form of button shown in Figs. 3, 4, 7, and 10, of the drawing, the outer projecting end 4c of the shank has a bore 8 into which is received a humped spring pin 9 having a head 10 disposed in a plane at right angles to the plane of the 35 hump in the pin.

Attention is now called to a very important 40 feature of the working face of my traverse button, which feature is more clearly illustrated in Figs. 12 and 13 of the drawing, from which it will be seen that the face of the button is not spherical, but rather cylindrical, in its transverse direction. That is to say; it presents a broad, convex, cylindrical face 11 to the cop as it moves back and 45 forth thereupon in feeding the thread thereto and laying it thereupon.

50 In operation, the shank of the button is inserted in the opening 5 between the jaws 3 of the holder, in the usual way, with the top face of the button in engagement with the under side of the holder. This brings the parallel grooves 6 just above the face of the jaws 3. The U-shaped spring wire 7 has its 55 inwardly-inclined free ends sprung slightly outward and entered in the grooves 6 of the shank of the button, as illustrated in Fig. 2 of the drawing. This brings the under side of the spring wire 7 into engagement with the upper face of the jaws 3, and locks the shank 60 of the button against up-and-down movement in the holder 1, so that no amount of vibration can ever cause it to fall out, even though the jaws 3 may have become somewhat sprung. Neither will the spring lock 7 ever work out 65 from vibration, since its two opposite sides

are naturally sprung inwardly slightly toward each other at their free ends, so that they automatically grip the shank of the button in the grooves 6. Hence it becomes apparent that no shellacking or cementing of the 70 buttons in their holders is ever necessary. And yet whenever it is necessary to remove a button for replacement purposes, or for any other cause, it can be easily and quickly done by any one, even a child; and the 75 metal holder does not have to be discarded in cases where the shank of the button is easily inserted into it.

In the modified form of button shank shown in Figs. 3, 7, and 10, the bore 8 and 80 the humped spring pin 9 take the place of the grooves 6 and the U-shaped spring 7 of the other form, to hold the top face of the button in engagement with the under side of the holder 1, as shown in Fig. 4 of the 85 drawing. The head 10 of this pin, being disposed in a plane at right angles to the plane of the hump, keeps the pin from turning in the bore 8, while the hump forms a 90 spring pressing upwardly in the bore 8, and thus yieldingly presses the upper face of the button into constant engagement with the under side of the jaws 3.

When the button is at work copping 95 thread, the broad cylindrical face 11 presses 100 evenly upon a considerable area of the cop since it lies in parallel engagement therewith for a material distance at each side of the point where the thread is being delivered to the cop, and as a result this arrangement insures a very tight, evenly wound, compact cone, so that the weight of the cone can be 105 very accurately gauged, in addition to the fact that it produces a cone of exceptionally fine appearance, thus easily commanding the 110 top of the market.

Having now described my invention, what I claim as new, and desire to protect by Letters Patent is:—

1. In combination, a traverse button and 110 a holder therefor, the button having a shank, and the holder having an opening for receiving the same, said shank projecting beyond the side of said holder into which it is received, said projecting portion having an 115 opening; and an upwardly-humped spring pin for extending through said opening to hold the button on the holder, said pin having a T-head extending in a direction at right angles to the plane of said hump.

2. In a device of the character described, 120 a traverse button having its working side in the form of a spherical surface cut away centrally across the face thereof to produce a 125 zone in the form of the segment of a cylinder extending in the direction in which the button is designed to travel on the cone, said zone merging at each side thereof into said spherical surface.

3. In a device of the character described, 130

a traverse button having its working side in the form of a spherical surface cut away centrally across the face thereof to produce a zone in the form of the segment of a circle extending in the direction in which the button is designed to travel on the cone, said zone merging at each side thereof into said spherical surface, said spherical surface extending from said zone on either side thereof to the edge of the button.

In testimony whereof I affix my signature.
JESSE F. MADDEN.
